UNITED STATES PATENT OFFICE.

WALTER J. KIRCHNER, OF SAN FRANCISCO, CALIFORNIA.

DESIGN FOR A HAT AND COAT HOOK.

40,578.

Specification for Design.

Patented Mar. 15, 1910.

Application filed January 20, 1910. Serial No. 539,203. Term of patent 7 years.

To all whom it may concern:

Be it known that I, WALTER J. KIRCHNER, a citizen of the United States, residing at San Francisco, in the county of San Francisco and State of California, have invented a new, original, and ornamental Design for Hat and Coat Hooks, of which the following is a specification, reference being had to the accompanying drawing, forming part thereof.

The figure is a front elevation of a hat and coat hook, showing my new design.

I claim:

The ornamental design for a hat and coat hook, as shown.

W. J. KIRCHNER.
